[57]**CLAIM**

The ornamental design for a tip portion of a resectoscope electrode, as shown and described.

DESCRIPTION

FIG. 1 is a perspective view of a tip portion of a resectoscope electrode showing our new design, the broken line showing of the electrode lead is for illustrative purposes only and forms no part of the claimed design;

FIG. 2 is an enlarged perspective view thereof;

FIG. 3 is a top view thereof;

FIG. 4 is a side view thereof;

FIG. 5 is a bottom view thereof;

FIG. 6 is a end view thereof; and,

FIG. 7 is a rear view thereof.
